United States Patent

Des. 240,935
Patented Aug. 10, 1976

240,935

COMMERCIAL TELLER TERMINAL OR SIMILAR ARTICLE

William L. King, Dayton, and Thomas L. Hermann,
Springfield, Ohio, assignors to NCR Corporation

Filed Dec. 23, 1974, Ser. No. 535,923

Term of patent 14 years

Int. Cl. D20—02

U.S. Cl. D26—5 C

FIG. 1

FIG. 2

FIG. 3

FIG. 4

FIG. 5

FIG. 1 is a left, front, perspective view of a commercial teller terminal or similar article showing our new design;

FIG. 2 is a right, front, perspective view thereof;

FIG. 3 is a left, side, elevational view thereof;

FIG. 4 is a right, side, elevational view thereof; and

FIG. 5 is a rear, elevational view thereof.

We claim:

The ornamental design for a commercial teller terminal or similar article, as shown and described.
